UNITED STATES PATENT OFFICE

LESTER A. JAMES, OF OKLAHOMA CITY, OKLAHOMA

HEATING AND COOLING DEVICE FOR INCLOSED SPACES

Application filed May 14, 1928. Serial No. 277,552.

My invention relates to devices for controlling the temperature of inclosed cars and for cooling and supplying drinking water therein.

- 5 The objects of the invention are to provide a device which will exhaust the air in the car by fan suction, force the air through a cooling device where its temperature is lowered and then return it to the car; to provide a device which will also operate to heat the air by exhausting it from the car, forcing it through a heater and back into the car; also to provide a device for applying heat to the windshield so as to prevent the formation of frost thereon; also in connection with the cooling device to provide a supply of cold drinking water and having same easily accessible, as on the instrument board; to provide such units for cooling and heating which 10 are new, simple, light, strong, durable, inexpensive, reliable and of evident utility; which cannot easily get out of order when once installed and which are efficient for the purposes for which they are intended.
- 15 25 With these and other objects in view, my invention consists of the construction, novel features and combination of parts hereinafter more fully described, illustrated in the accompanying two sheets of drawings and pointed out in the claims hereto appended, it being understood that various changes in the form, proportion, size, shape, weight and details of construction, within the scope of my invention may be resorted to without departing from the spirit or principle of the invention or sacrificing any of the advantages thereof.

In the accompanying drawings Figure 1 is a fragmentary sectional view of a car showing the devices attached; Fig. 2 is a perspective view of the cool air vent and by-pass to the heater; Fig. 3 is a sectional view through the cooling device; Fig. 4 is a sectional view on the line 4-4 of Fig. 3; Fig. 5 is a sectional view of an alternate form of cooling device; Fig. 6 is a sectional view through the heater showing a portion of the hot air ventilator in section; Fig. 7 is a perspective view of an application of the heating device to the windshield; Fig. 8 is a per-

spective sectional view showing openings in parts adjoining the windshield; and Fig. 9 is a fragmentary perspective view showing a part of the cooling device and drinking water spigot.

Like numbers of reference will be used for the same parts throughout all the views.

Traveling salesmen, as well as others whose business requires them to drive in all kinds of weather, suffer great discomfort from the extremes in temperature. In cold weather it is difficult to keep the hands and feet warm and there is danger in driving when frost and ice collects on and obstructs the view through the windshield. In warm weather when windshield and windows must be left open for ventilation there is the annoyance of dust and insects, and the lack of a cold drinking water supply. My invention seeks to eliminate all of these annoyances and disadvantages.

In Figure 1, the numeral 1 represents the car body, 2 is the air suction pipe, 3 is a fan or blower operated by the fan motor 4, connected with the battery by line 5; the hose 6 connects the fan with the cooling device consisting of an outer casing 7 for insulating and inclosing the other parts of the cooler. At 8 is a bottom hollow ring member or manifold into which the air is forced by the fan through the hose 6. Here the air is split up into small currents and forced upward through the air tubes 9, said tubes being surrounded by cold water; the cooled air currents in the said tubes 9 are collected in a top hollow ring member or manifold 10 ready to be forced through connection 21 as will be explained presently. Within the casing 7 of the cooler is the cold water cylinder through which the said tubes 9 pass. This consists of an outer shell 11 and an inner shell 12. At 13 is a water filling compartment provided with a filling tube and cap 14. Within the said inner shell 12, but separated therefrom by an air space, is the ice and ice water tank 15, provided with a filling tube and cap 16, the said cap having an air valve 17 by means of which air pressure may be supplied to the ice and ice water tank 15. As can best be seen in Figs. 3 and 4 the outer casing 7

of the cooler completely insulates the water compartments so that only a small amount of ice in the tank 15 will be necessary to the efficient operation of the cooler. Leading out 5 from the bottom of the tank 15 is the drinking water supply pipe 18 terminating in a conveniently placed spigot 19, provided with waste cup and pipe 20. The connection 21 leads out from the cooling device and terminates 10 in the cool air vent 22, which has a series of perforations in its top through which the cooled air is admitted to the interior of the car near the floor. The said vent 22 is provided with a sliding top cut-off or 15 damper 24 by means of which the cooled air can be shut off, thus converting the said vent into a by-pass to the heater. When used to heat the car, the air circulates through the cooler as just described but without the use 20 of ice, the damper 25 in the bottom of vent 22 is opened by means of handle 26, the air is forced through connection 27 to the air heater 28, into distributing chamber 29 where it is broken up and passes through the hot 25 air tubes 30 and into the collecting chamber 31, the said hot air tubes 30 and chambers 29 and 31 are mounted upon the exhaust manifold 32. After being heated the air is forced through passage 33 and hot air ventilator 34 30 and into the car at the driver's feet, the said ventilator 34 being provided with a damper 35. Taking off from passage 33 is hot air pipe 36, with a conveniently placed valve 37, flexible connection 38 and hot air supply conduit 39 attached to the upper edge or any 35 suitable place on the windshield 40 by suitable holding means 40a. By this means the glass is kept warm, thus preventing the formation of frost and ice on both sides of the 40 said windshield and assuring clear vision through the same at all times. In Fig. 5 is shown an alternate form of cooling device consisting of an outer insulating shell 41, an ice and ice water tank 42 connected with a 45 series of felt encased tubes 43 kept moist by the ice water, the air entering at 44, passing around and through the said tubes 43 and out at 45, thence to cool-air-vent 22. Air pressure can be applied to tank 42, forcing the 50 ice water out through pipe 46 and to spigot 19. From the foregoing description it can be seen that I provide means for keeping the interior temperature of the car fairly constant and always comfortable at all seasons 55 of the year, a supply of cold drinking water when needed and a valuable safe guard in a clear windshield during cold, sleety weather.

Having thus described the invention what is claimed and desired to be secured by Letters Patent is:

1. In an automobile including an inclosed car and an internal combustion engine having an exhaust manifold, the combination with air cooling means, fan means for exhausting a portion of the air from the body

of the inclosed car, and forcing it through said cooling means, means for returning the cooled air to the inclosed part of said car, and means for shutting off said cooled air returning means, of means for converting said cooled air returning means into a by-pass for conveying the air to a heating means, said heating means, comprising a distributing heating chamber adjacent said exhaust manifold, and also comprising a plurality of hot air tubes for breaking up and better heating the air currents, and a chamber for collecting said heated air currents, conveyor means for conveying the heated air to a ventilator in the interior of the vehicle and damper means for controlling said ventilator.

2. In an automobile including an inclosed car and an internal combustion engine having an exhaust manifold, the combination with air cooling means, fan means for exhausting a portion of the air from the body of the inclosed car and forcing it through said cooling means, means for returning the cooled air to the inclosed part of said car, means for shutting off said cooled air returning means, of means for converting said cooled air returning means into a by-pass for conveying the air to a heating means, said heating means, comprising a distributing heating chamber adjacent said exhaust manifold and also comprising a plurality of hot air tubes for breaking up and better heating the air currents, and a chamber for collecting said heated air currents, conveyor means for conveying the heated air to a ventilator in the interior of the car and damper means for controlling said ventilator, a flexible take-off pipe for connecting said heat-conveying means with a conduit, means for opening and closing said pipe, and a conduit adapted for connection to a suitable part of said car for conveying and delivering heated air thereto.

3. An air cooling device for vehicles, embodying an outer hermetical casing, an annular bottom manifold within and spaced from said casing, said manifold having an air inlet pipe, a plurality of vertical spaced air tubes connected to the top of said manifold, an upper annular manifold connected to the top of said tubes and also spaced from the walls of said casing, said upper manifold having an air outlet pipe, an annular inner casing extending between said manifolds and hermetically enclosing said tubes, means for supplying water within said inner casing around said tubes, an ice compartment surrounded by and spaced from said inner casing, and means for circulating air through said inlet pipe into said lower manifold, through said air tubes into said upper manifold, and from said upper manifold through said outlet pipe to the interior of said vehicle.

4. An air cooling device for vehicles, em-

bodying an outer hermetical casing, an annular bottom manifold within and spaced from said casing, said manifold having an air inlet pipe, a plurality of vertical spaced 5 air tubes connected to the top of said manifold, an upper annular manifold connected to the top of said tubes and also spaced from the walls of said casing, said upper manifold having an air outlet pipe, an annular inner 10 casing extending between said manifolds and hermetically enclosing said tubes, means for supplying water within said inner casing around said tubes, an ice compartment surrounded by and spaced from said inner casing, 15 means for circulating air from the interior of the vehicle, through said inlet pipe into said lower manifold, through said air tubes into said upper manifold, and from said upper manifold through said outlet 20 pipe back to the interior of said vehicle.

5. An air cooling device for vehicles, embodying an outer hermetical casing, an annular bottom manifold within and spaced from said casing, said manifold having an 25 air inlet pipe, a plurality of vertical spaced air tubes connected to the top of said manifold, an upper annular manifold connected to the top of said tubes and also spaced from the walls of said casing, said upper manifold having an air outlet pipe, an annular inner 30 casing extending between said manifolds and hermetically enclosing said tubes, means for supplying water within said inner casing around said tubes, an ice compartment surrounded by and spaced from said 35 inner casing, means for circulating air from the interior of the vehicle, through said inlet pipe into said lower manifold, through said air tubes into said upper manifold, and from said upper manifold through said outlet 40 pipe back to the interior of said vehicle, a valve for diverting the air from said outlet pipe to a pipe leading to the vehicle engine, a heating chamber connected to said 45 last named pipe and surrounding the vehicle engine exhaust manifold, a plurality of heating pipes within said heating chamber and spacedly surrounding said manifold, said heating pipes adapted to receive air from 50 said last named pipe, a chamber for collecting the air leaving said heating pipes, and means for conveying the heated air to the interior of said vehicle.

LESTER A. JAMES.
